UNITED STATES PATENT OFFICE

2,436,070

CLOSET BEND COLLAR CONNECTION

Frank J. Lassa, Chicago, Ill.

Application October 28, 1944, Serial No. 560,839

1 Claim. (Cl. 285—34)

1

My invention relates to fittings for closet bowls and more particularly to the collars used in connecting the base of the bowl to the waste pipe bend.

In installations of the above character, the securing bolts are applied with heads under the flange of the bend collar rising upwardly through the bowl base to receive cap nuts while the floor under the said flange usually lacks sufficient friction for the head of the bolt to keep the latter from turning as the cap nut is applied. Many times this does not occur, and the bolt keeps on turning with the nut and making the task difficult and slow.

It is therefore one object of the present invention to modify the collar in a manner to lock the bolt after it has been applied, so that it may not turn as the nut is mounted and screwed down.

A further object of the invention is to modify the collar in a manner to permit the standard bolt to be used, so that no special provision need be made or parts secured for that purpose.

Another object of the invention is to construct the collar along lines of extreme simplicity and without the addition of any parts thereto for the accomplishment of the present purpose.

An important object of the invention is to provide an improved collar whose cost will only slightly exceed that of the conventional collar.

With the above objects in view and any others which may suggest themselves from the description to follow, a better understanding of the invention may be had by reference to the accompanying drawing, in which—

Fig. 1 is a side elevation of a conventional closet bowl installation, showing its base connections in section;

Fig. 2 is a top plan view on an enlarged scale of the improved collar;

Fig. 3 is a similar fragmental view on a further enlarged scale showing the manner in which the attaching bolt is locked; and

Figs. 4 and 5 are, respectively, sections on the lines 4—4 and 5—5 of Fig. 3.

Referring specifically to the drawing, the closet bowl is indicated at 10 and its base at 11. Generally, the closet bend collar 12 appears to be of standard form, having the usual flange 13 at the top and the supporting joint 14 at the bottom for the waste pipe bend 15. Fig. 1 shows that the base 11 rests on the floor 16 of the premises in which the closet bowl is installed, and that the said floor is somewhat recessed as indicated at 17 to flushly seat the collar flange 13.

As was previously mentioned, a slight amount

of clearance is usually present in the floor below the collar flange 13 in order that the heads of the bolts may find room under the flange. The bolt under consideration is indicated at 18, and its head 19 is in the nature of a thin, elongated plate, preferably rounded at the ends as indicated at 20. In the novel embodiment, I do not apply the head of the bolt beneath the collar flange 13, but lower the bolt head directly into an opening 21 in the top face of the side flange. As indicated more clearly in Fig. 3, the opening referred to is similar in form and somewhat larger than the head 19 of the bolt. Also, the opening is extended on opposite sides with a pair of lateral cavities 22 whose outer limits or side walls are sufficiently spaced to permit the bolt to be turned crosswise and with the end portions of its head 19 lodged in the cavities 22 as indicated by dotted lines in Fig. 3. As seen in this figure, the clockwise turning of the bolt—that is, in the same direction as the cap nut 23 applicable above would be turned—locates its head 19 crosswise of the opening 21; and in this position the end portions of the head are designed to meet end walls 24 of the cavities 22.

It will be evident from the above explanation that when the head of the bolt 18 has once assumed the position just described, it is locked both from being raised out of the opening 21 as well as from turning any further. Thus, when the cap nut 23 is applied and screwed down, the bolt will not turn beyond the position mentioned and remain still while the cap nut is being turned. Since the regular thickness of the collar flange 13 will be insufficient to accommodate the cavities 21 and leave enough top and bottom stock in the flange, the latter is thickened downwardly as indicated at 25 in the region of the cavities 22. Fig. 5 shows this feature more clearly, and the same will either find the necessary clearance in the floor 16 or require very little work to produce the same.

It will be evident from the above description that I have improved the closet bend collar in a manner to eliminate the application of the bolt or any other fastening means underneath the flange 13, that is, any place where it is difficult or not feasible to keep the head of the bolt from turning. On the other hand, the bolt is now entirely within and above the collar flange, and its application is in the open by simply lowering the bolt with its head in the opening 21 and giving the bolt a quarter-turn to lock it as described. The closet bowl base may now be lowered to receive the bolt and permit the applica-

tion and quick fastening of the cap nut 23. An improvement is thus had which makes no alteration in the bolt, and only requires the collar to be cast with a special core, occasioning but a slight extra expense in its manufacture when this is done on a production basis. The collar therefore remains in a single piece, and no extra part is added to the installation for the purpose of the present invention. The improvement thus makes the application of the bolt and its fastening a simple and quick operation.

While I have described the invention along specific lines, various minor changes or refinements may be made therein without departing from its principle, and I desire to consider such changes and refinements as coming within the scope and spirit of the appended claim.

I claim:

A closet bend collar assembly for connection to the perforated base of a closet bowl resting on said collar, said collar assembly including a collar member comprising an annular horizontal upper flange and an inner vertical depending portion, said horizontal flange having a pair of

opposed thickened sections formed in the lower face thereof, each of said thickened sections having an elongated opening and a pair of oppositely disposed cavities leading from said opening, each of said cavities being defined by an upper wall, a bottom wall, a side wall and an end wall, said assembly further including a bolt having a head complementary in shape but of slightly smaller size than said elongated opening, whereby upon insertion of said head in said opening and turning thereof will seat same between the top and bottom walls of said cavity, and into abutting relationship with the end wall thereof.
